J. TORRES

SHAMPOO STAND

Filed April 22, 1926

Patented Aug. 10, 1926.

UNITED STATES PATENT OFFICE.

JOSEPH TORRES, OF BROOKLYN, NEW YORK.

SHAMPOO STAND.

Application filed April 22, 1926. Serial No. 103,737.

This invention relates to an improvement in shampoo stands for shampooing ladies' or gentlemen's hair. It is an object of the invention to provide a portable and adjustable shampoo stand of small dimensions and light weight which may be moved from place to place without disturbing the drainage connection and which will occupy only a small space on the floor of the beauty 10 parlor or barber shop.

Another object of the invention is to provide a shampoo stand in which the space from the rear to the front of the stand is reduced to a minimum to permit the person doing the shampooing to walk around the stand to reach the head of the person having the shampoo with the greater ease.

Another object of the invention is to provide a shampoo stand arranged for the convenience of the person doing the shampooing wherein the materials and appliances used during the shampoo will be within easy and ready reach and the height of the stand will be such as to reduce the labor of giving 25 a shampoo.

Another object of the invention is to provide a shampoo stand of the type described with flexible connections to the sewer or drain pipes and to provide a means for collecting the loose hair and dirt from the shampooing in the stand to prevent clogging the drain pipe.

Another object of the invention is to provide a shampoo stand having the conveniences and advantages above noted which will be of neat and attractive appearance and which may be manufactured and sold at comparatively low cost.

Other objects and advantages of the invention will appear as the description thereof proceeds.

Referring now to the drawings, which show a preferred form of embodiment of my invention:

Figure 1 is a plan view of my improved shampoo stand;

Figure 2 is a sectional view approximately on the center line of Figure 1;

Figure 3 is a perspective view showing 50 the position of the shampoo stand when in use;

Figure 4 is a detailed view of a particular type of shampoo nozzle adapted for use on my shampoo stand; and

Figure 5 is a sectional view on line 5-5 55 of Figure 2.

In the embodiment chosen to illustrate the invention, the stand comprises a semi-circular basin 1 of sufficient depth and size to receive the water used in the shampoo and to permit it to drain out without overflowing and an apron 2, which is preferably integral with the front edge of the basin 1 and projects outwardly in approximately a horizontal plane so as to bring the apron 65 and the top of the basin to approximately the same height. The apron 2 includes a pair of forwardly projecting ledges 3 with an intermediate recess 4, which is adapted to fit around the back of the neck of the person having the shampoo, as shown in Figure 3, with the ledges 3 projecting forwardly at each side to about the front of the head. A bead or rim 5 is provided around the outer edge of the apron 2, ledges 75 3, and recess 4 and along the back of the recess 4 the height of the bead 5 is preferably increased as indicated at 5^a to prevent the excess of water which falls on the apron at this point from overflowing 80 on the person who is taking the shampoo. The apron 2 preferably slopes from the outer edges toward the center and from the front of the apron toward the back or basin 85 so as to provide for drainage from all portions of the apron into the basin 1. The rear wall 6 of the basin 1 is substantially a diameter of the circle on which the basin 90 is formed dividing the basin into a semi-circle and reducing the width of the basin 90 as well as providing a straight wall along the back thereof. This permits the person doing the shampooing to come near to the person being shampooed in walking around the stand, so as to make it more convenient 95 to give a shampoo with the use of this apparatus and at the same time reduces the room occupied by the stand when not in use. The bottom of the basin 1 is provided with a drainage outlet 7 which may 100 be connected by means of the hose or the like 8 with a drain pipe to the sewer and to prevent loose hairs and other refuse from entering and clogging the drain pipes, a perforated strainer 15 is located at the entrance 105 to the outlet 7 so as to catch and retain the hairs or the like in the basin 1 from which they may be readily removed. A boss 9 connected with the drainage outlet 7 by means of a reinforcing rib 10 is also provided at 110 the bottom of the basin 1 and is adapted to receive one end of an adjustable stand 11,

supported on a rolling tripod 12, so as to permit ready movement of the stand over the floor of the shop. To adjust the stand to the height of the head of the person being shampooed, the thumb screw 13 is loosened and the stand 11 of the stand raised or lowered to the desired extent, whereupon the stand may be slid forward on the floor to the chair in which the person having the shampoo is seated and pushed forward so that the recess 4 fits on the back of the neck of the person 14 who is receiving the shampoo. To facilitate the work of the person giving the shampoo, the straight edge of the basin 1 is preferably provided with a notch 16 adapted to receive the stem 17 of the shampoo spray 18, which is connected by means of the flexible hose 19 with suitable hot and cold water connections, so that when not in use, the spray 18 may be inserted in the notch 16 with the open end of the spray over the basin so that any drippings will fall into the basin. When it is desired to use the spray, the operator has only a slight movement of his hand to grasp the stem 17 and direct the spray to the point desired on the hair. As a further convenience, the basin 1 may be provided with supports 20, suitably secured to the inner walls of the basin and adapted to support a bottle 21 for containing a shampoo liquid or other shampooing accessory. The stand 20 is preferably provided with a spring clip 22 which projects above the side of the stand and partially encircles the edge of the bottles so that the bottles will not be upset when the stand is moved back and forth over the floor. By supporting the bottles above the bottom of the basin 1, they are kept out of contact with the drainage water in the basin and are therefore substantially dry when picked up by the person doing the shampooing, so that there is no annoying dripping from these bottles.

I prefer to make the basin 1 and apron 2 of an integral lightweight casting, such as aluminum, which may be readily supported by means of the boss 9 from the stand 11. In this way the cost of the apparatus is reduced over that of providing an enamelled basin and apron, cracking and chipping of the enamel is avoided and the cast aluminum basin and apron may be easily kept clean and in polished condition. It will be seen that the number of parts of my apparatus are exceedingly few and of simple construction, so as to be easy to produce and that the shampoo stand provides a most convenient assembly and lay out for the person giving the shampoo. The apron and basin are supported about the waist height of the person giving the shampoo, all of the necessary shampoo articles are supported in the basin and out of contact with the drainage water and the stand is readily movable over the floor of the shop and readily adjustable to different heights.

While I have illustrated and described one embodiment of my invention, it is to be understood that various modifications and changes may be resorted to without departing from the spirit of the invention or the scope of the appended claims.

What I claim as my invention is:—

1. In a shampoo stand, a semi-circular basin, a drainage outlet for said basin, an apron extending outwardly from one edge of said basin, in approximately the plane of the top of said basin, said apron being sloped to drain into said basin, a recess in said apron adapted to fit around the neck of the person receiving the shampoo, and a portable stand for supporting said basin and apron. 75
2. In a shampoo stand, a semi-circular basin, a drainage outlet for said basin, a hair strainer in said drainage outlet, an integral apron projecting outwardly from the curved edge of said basin in approximately the top horizontal plane of said basin, said apron sloping from its outer edges toward said basin, a recess in said apron adapted to fit around the neck of the person receiving the shampoo, a bead around the edge of said apron, a portable stand for supporting said basin and apron and means on said stand for adjusting the height of the basin. 85
3. In a shampoo stand, a semi-circular basin, a drainage outlet for said basin, a strainer at the entrance to said drainage outlet, flexible means for connecting the drainage outlet with the sewer, a substantially horizontal apron projecting out from one edge of said basin, said apron sloping toward said basin, a recess in said apron fitting the neck of a person, a substantially flat ledge projecting outward at each side of said apron and adjustable means to support the basin and apron at approximately the height of the shoulder of the person receiving the shampoo. 95

In testimony whereof I have affixed my signature to this specification.

JOSEPH TORRES. 110
